RAZOR, SHARPENER, RAZOR BLADE SHARPENING INSTRUMENT, AND RAZOR BLADE

Hugh De Haven, New York, N. Y.

Application December 9, 1929, Serial No. 412,592

45 Claims. (Cl. 30—12)

This invention relates to a razor blade sharpening instrument and in particular to a razor of the type containing a blade and a blade edging element mounted on the sharpener or razor to move in contact with the edge of the blade for sharpening it.

One of the objects of the invention is a novel blade edging element or sharpener to be mounted on the sharpening instrument or razor and to reciprocate relatively to the blade and in contact with the blade for sharpening the blade edge.

Another object of the invention is a razor blade.

Another object of the invention is a method of sharpening a razor blade.

Another object of the invention is a razor of the type described, so constructed as to permit the adjustment of the guard relative to the edge of the blade.

Other objects and features of the invention will more fully appear from the following description and the accompanying drawings and will particularly be pointed out in the claims.

The drawings show in section, elevation and detail a preferred form of construction of the razor, of the blade, and of the sharpener or blade edging element, and the parts thereof, and illustrate the broad principles of the invention.

In the drawings:

Fig. 1 is a front elevation of the razor.

Fig. 2 is a side elevation of the razor.

Fig. 3 is a rear elevation of the razor.

Fig. 4 is a longitudinal section through the razor with the parts in shaving position, that is, with the blade edging device in retracted or housed position and with the blade holder in closed position.

Fig. 5 is a section similar to Fig. 4, but showing the blade edging device in extended position.

Fig. 6 is a view of the blade showing the body portion and the backing.

Fig. 7 is a rear view of the backing of the blade.

Fig. 8 is a section on line 8—8 of Fig. 6, looking in the direction of the arrow.

Fig. 9 is a section on line 9—9 of Fig. 6, looking in the direction of the arrows.

Fig. 10 is a view similar to Fig. 4, but showing the head of the razor with the blade holder in open position.

Fig. 11 is a view of the head of the razor as seen from the front with the blade holder in open position.

Fig. 12 is an enlarged perspective view of the blade holder.

Figs. 13 and 14 are plan views of different forms of sharpeners or blade edging elements which may be used.

Fig. 15 illustrates the contact between the sharpener and a blade which is irregular due to a warp.

Fig. 16 illustrates the contact between the sharpener and a perfectly regular blade.

Fig. 17 illustrates the contact between the sharpener and a blade which is irregular both along its length and across its width.

Fig. 18 is an enlarged view on line 18—18 of Fig. 13, looking in the direction of the arrows.

Fig. 19 is a front elevation of a slightly different form of the razor.

Fig. 20 is a longitudinal section through the razor, as shown in Fig. 19.

The parts of the razor may be designated generally as a handle 1, a blade holder 2 and a blade edging device 3. The handle may be formed of any suitable material, but is preferably of a non-corrosive or non-rusting material stamped to provide upright portions 4, upper parts 5 which extend outwardly at an angle to the portions 4, and then again extend upwardly at 6 to form separated arms and to provide, with the associated parts of the razor, a head. The term "head" is used to denote generally the upper part of the razor, including the blade holder 2.

The razor is intended to be used for shaving with the parts in the position shown in Figs. 2 and 4. For sharpening the edge of the blade, the sharpening device is reciprocated relatively to and in contact with the blade, for example, from the position shown in Fig. 4 to the position shown in Fig. 5, by shaking the razor. For cleaning the razor and removing the blade, the blade holder is opened to the position shown in Fig. 10.

The sharpening device includes the sharpener 7 and may include also the plate 8 on which the sharpener 7 is mounted. The forward edge of the plate 8 may be serrated or cut to form the guard teeth 9. In order to enable the sharpener 7 to reciprocate in contact with the edge of the blade, the plate 8 is mounted on a stem 10, which is pivoted on a pin 11 in the handle of the razor. Wings 12 on the stem 10 cooperate with other wings 13 on the parts 4 of the handle to limit the movement of the sharpener and its associated parts, from the position shown in Fig. 4 to the

position shown in Fig. 5, it being evident that as the stem 10 moves from the position shown in Fig. 5 to the position shown in Fig. 4, the wings 12 on the stem engage the wings 13 on the parts 4 of the handle to limit the forward movement of the stem and consequently the forward movement of the sharpener. The wings 12 and 13 are so positioned that the sharpener never moves far enough forward for the razor blade to pass off of the rear edge of the sharpener.

In order to obtain an even contact between the edge of the blade and the sharpener, the sharpener is so mounted that it may move to adjust itself on its support to permit the sharpener and blade to lie in parallel contact with each other. For this purpose there is a pivotal connection, preferably at a right angle to the front edge of the sharpener, between the stem 10 and the sharpener 7. This pivotal connection may be made by providing ears 14 on the top of the stem, which enclose between them a tab or projection 15 which extends downwardly from the plate 8 which supports the sharpener. The tab 15 is preferably smaller than the space between the ears 14, so that the tab may be moved to the right or to the left, as seen in Fig. 4, that is from the back to the front of the razor to adjust the position of the guard 9 relative to the edge 16 of the blade. The tab 15 may conveniently be provided with a threaded hole to receive the screw threaded sleeve 17 which may be rotated by the knurled head 17'. The sleeve is mounted for free rotation on the screw 18, which passes through an opening in one of the ears 14 and is screw threaded at 19 into the other ear. The head 17' of the sleeve may conveniently surround the head 20 of the screw and the body of the sleeve 17 preferably extends only to the ear 14 which is remote from the head 17' of the sleeve, so as not to interfere with the threaded connection between the end 19 of the screw 18 and the cooperating ear 14. The head 17' of the threaded sleeve may be rotated to rotate the sleeve and thereby to move the tab 15, together with the plate 8 and the sharpener 7, to the right or to the left of Fig. 4 to make the guard teeth 9 lie farther in front of or in back of the edge 16 of the blade. The opening in the ear 14 through which the sleeve 17 passes, is large enough to permit the sleeve to rotate quite freely in order that the sharpener may move easily to adjust itself to lie in parallel contact with the blade edge 16. With this construction the sharpener 7 and the plate 8 are removable from the stem 10 merely by unscrewing the screw 18 and pulling it out of the ears 14 together with the threaded sleeve 17', the sharpener and plate are also adjustable by means of the sleeve 17 to change the position of the guard teeth 9 relative to the edge 16 of the blade to give close shaves; and, furthermore, the sharpener may move to adjust itself on its support to permit the blade and sharpener to lie in parallel contact with each other.

The stop pin 21 is in position to engage the stem 10 for limiting its backward movement and giving the stem a fixed position, so that when the plate 8 is retracted, the guard 9 will be in the desired position relative to the edge 16 of the blade. The stop pin 21 also serves to strengthen the construction and to space the upper ends of the parts 4 of the handle so that the wings 12 on the stem do not bind against the parts 4 and the stem and sharpener can have a slight amount of

side movement. The stem 10 is preferably provided with a notch 22, within which the pin 21 may be received so that the stem may be fully retracted and housed within the handle.

In the form of razor shown in Figs. 19 and 20, the stem 10 is provided with a bearing 23 and the plate 8 is provided with tabs 24 which fit over and enclose this bearing 23. One of the tabs 24 is provided with a threaded opening to receive the threaded end 25 of the pivot pin 26, which extends through the other tab 24 and through an opening in the bearing 23. With this arrangement of parts there is no adjustment of the guard relative to the edge 16 of the blade, but the plate 8 and sharpener 7 may easily be removed by revolving the pivot pin 26 to screw the end 25 out of the threaded opening in the tab 24, after which the pin 26 may be pulled all the way out of the bearing 23 and the other tab 24 to permit the disassembling of the parts. In order to position the guard relative to the blade in the form of razor shown in Figs. 17 and 18, the plate 8 may conveniently be provided with projecting ears 27, which engage with the outwardly extending parts 5 of the razor handle.

The blade, which includes the body portion 28, the backing 29 and connecting parts 30, which will later be described in more detail, is held in the blade holder denoted generally at 2.

The blade holder may conveniently be made of a single piece of springy metal having the gripping parts 31 and 32 which enclose and engage the rigid backing 29 of the blade. The gripping part 32 of the blade holder is preferably a lip which is curved to enclose the backing 29 of the blade with the edge 33 of the lip over the ridge 34 on the backing 29 of the blade. This securely holds the blade in the blade holder and to insert the blade in the blade holder, the blade holder is raised to the position shown in Fig. 10 and the blade is pushed in from the side of the blade holder, so that the edge 33 of the lip 32 rides over the ridge 34 of the blade backing. The engagement of the edge 33 of the lip 32 with the ridge 34 holds the backing of the blade seated between the gripping parts 31 and 32 of the blade holder. To give additional holding properties, a spring 35 is preferably struck up from the back of the blade holder.

This spring holds the backing 29 of the blade against and under the lip 32 but yet may yield to enable the blade easily to be withdrawn or inserted. The lip 32 and the spring 35 therefore cooperate to hold the blade in the blade holder, each exerting a force to keep the backing of the blade in engagement with the lip 32 and each holding the backing of the blade seated in the blade gripping parts 31 and 32 of the blade holder. In order to enable the blade easily to be inserted into the blade holder, the ends 36 of lip 32 are spread more than the central portion and the ends of the backing are tapered as is shown in Figs. 6 and 7 to come substantially to a point 37 on each end of the backing. The taper extends at 38 upwardly from the bottom of the backing toward the points 37 and the ridges 34 extend downwardly at 38' from the center of the backing toward the points (as is shown most clearly on Fig. 6), and at 39 the taper extends on each side of the backing toward the points 37 (as is shown most clearly on Fig. 7). This enables the backing easily to be inserted into and then forced past the lip 32 and the spring 35. In order to positively position the blade holding lip 32 the bottom of the lip 32 is preferably embossed at 40 to 150

strengthen it at this point and the bottom of the backing is cut away at 41 to avoid any contact at this point so as to prevent rocking of the blade and to enable it to rest steadily in the holder on the points 42. The points 42 of the blade backing 5 rest on the exposed surface of the part 43 of the blade holder and this two point contact between the backing of the blade and the part 43 of the blade holder serves to give a definite position to the edge of the blade with relation to the guard, 10 as will later be explained. The tapering 39 of the backing begins at approximately the central portion of the backing, so that the central portion of the backing is the largest part. As a result of the bulge in the central portion of the 15 backing, the lip 32 and the spring 35 are enabled to secure their greatest grip when the blade is properly seated centrally within the blade holder to most securely hold the blade in position at that 20 point.

The blade holder is mounted on a rod 44 which extends across the head of the razor between the arms 6 and has squared ends 45 which extend through squared holes in the upper parts of the arms 6 to prevent the turning of the rod. The 25 blade holder has bearing parts 43 and 46 which contact with the rod 44 and the top of the blade holder extends from the forward edge 47 to provide another bearing part 48 so positioned that the bearing parts 43, 46 and 48 bear against the 30 rod 44 to hold the blade holder on the rod and permit it to be swung into any of the positions shown in Figs. 4, 5 and 10. The rod 44 is provided with a round part 49 and a flat part 50 so positioned with relation to the bearing parts 35 43, 46 and 48 of the blade holder that there is a spring action to yieldably hold the blade down against the sharpener when the parts are in the position shown in Figs. 4 and 5 and also to retain the blade holder in the open position shown 40 in Fig. 10. When the parts are in the position shown in Figs. 4 and 5, the bearing parts 43 and 46 are bearing on the round surface 49 of the rod 44 and the tendency of the bearing part 48 of the blade holder is to move into such a position 45 that it lies flat against the flat surface 50 of the rod. This gives a spring action tending to force the blade holder downwardly, so that the blade bears against the sharpener 7. The 50 downward force is sufficient to hold the blade in the shaving position shown in Fig. 4 and to prevent it from turning up during shaving and also to hold the sharpener in the retracted position shown in Fig. 4. When the blade holder is 55 in its raised position as is shown in Fig. 10, the bearing part 43 of the blade holder, which is purposefully made flat, lies flat against the flat part 50 of the rod 44 and the spring action is sufficient to retain the blade holder rather firmly in this 60 position. The under surface of the flat bearing part 43 thus serves to retain the blade holder in raised position and the upper surface is the seat for the points 42 of the blade backing. By having the backing of the blade cut away at 41 and 65 providing only the two points 42 at which the backing contacts with the part 43 of the holder, rocking of the blade is prevented and the cutting edge of the blade is definitely positioned relatively to the guard because the guard has a definite position relative to the handle through the ears 27 or through the stop pin 21, together with pivot 11, the blade holder also has a definite position relative to the handle through the rod 44, and the edge of the blade has a definite position relative to the handle and the guard through the 70 75

connecting parts 30 and the points 42 which always position the backing of the blade and therefore its cutting edge relative to the part 43 of the blade holder and therefore relative to the rod 44. The blade holder is preferably provided 80 with a finger piece 51 which extends from the bearing part 48 of the holder, so that by pressing down on the finger piece 51 the blade holder may be raised from the position shown in Fig. 4, to the position shown in Fig. 10. 85

One of the important features of the invention is the surface of the sharpener or blade edging element 7. It has been found that in the commercial manufacture of razor blades, the edges of the blades are quite irregular. If the edge of the average razor blade is brought into contact with a ground mechanically flat surface, certain portions of the blade edge will bear harder against the surface than others, due to irregularities in the edge. The average razor blade is 90 warped or otherwise irregular. Such blades may easily be sharpened on a leather strop, because the strop is soft and conforms itself to the irregularities in the blade, but such a blade cannot readily be sharpened on a hard surface on which 100 the blade may reciprocate while in contact therewith, because not all of the parts of the blade will contact with the surface. To overcome this difficulty, the blade sharpeners having the surfaces formed as shown in Figs. 13 and 14 have 105 been devised. The surface of the blade sharpener is provided with high portions 52 and low portions 53 and the difference in height between the high portions 52 of the sharpener and the low portions 53, is greater than the amount of 110 warp or irregularity in the edge of the blade. This may be explained in connection with the illustration shown in Figs. 15, 16 and 17. The line 54 in Fig. 16 is a straight line which represents the position of the edge of the blade if it 115 were straight. In order to sharpen the irregular blades such as are shown in Figs. 15 and 17, the raised portions 52 of the sharpener are high enough above the low portions 53, that when the raised portions enter the irregularities of the 120 blade edge (as is shown in Fig. 17), no other part of the blade edge will contact with the low portions 53 of the sharpener to prevent the raised portions 52 from effectively contacting the irregular part of the blade edge. The difference in 125 height between the high and low surface portions of the blade sharpener is sufficient to take care of the normal variations or irregularities of the average blade edge, as shown in Figs. 15 and 17. In Fig. 15 the full line 55 and the dotted line 56 130 show the action of a warped blade edge against a sharpening surface of the type referred to. In Fig. 17 the action of a generally irregular blade edge 57 is shown during the sharpening action.

The width of the high portions of the sharpener at any point where the shaving edge contacts therewith, should be less than the width of the irregularities in the shaving edge. This may be explained in connection with Fig. 17, from which it will be seen that the horizontal distance 135 between the point where the high portion 52 begins to rise above the low portion and the point at which the high portion again merges into the low portion (that is, the distance between the points 58 and 59) is less than the distance between the points where the irregularity in the blade edge begins and where it ends (that is, the distance between the points 60 and 61). Thus, the high portions of the sharpener are higher and less in width than are the irregularities in the 140 145 150

blade edge with the result that as the blade moves over the sharpener every point of the blade edge will contact with a part of the raised portion of the sharpener and all parts of the blade edge will be sharpened irrespective of the irregularities in the blade edge. The edge of the blade itself being slightly flexible will conform somewhat to the contour of the raised portion and will sharpen minor variations in the blade. The high portions of the sharpener are preferably continuous, forming a continuous, preferably V shaped, ridge with the sides lying at an angle to the edge of the blade, so that when the edge of the blade is in contact with the sharpener, it is always in contact, at some point, with the high portions throughout the reciprocation. The high portions of the sharpener also preferably extend far enough across the sharpener, so that all parts of the blade edge contact with the raised portions during the reciprocation of the sharpener. In the razor illustrated the sharpener is a little wider than the length of the blade edge and the high portions extend to the edges of the sharpener thus insuring that the edge of the blade contacts throughout its entire length. Some of the forms which the high portions may take, are shown in Figs. 13 and 14. In Fig. 13 the high portion is in the form of a V with the ends of the sides of the V substantially at the corners 62 and 63 of the sharpener and the angle 64 of the V is at such a distance from the forward edge of the sharpener that when the sharpener is in the extended position shown in Fig. 5, the edge of the blade is resting on the rear of the angle 64. The depth of the V shown in Fig. 13 therefore, will depend upon the length of stroke of reciprocation of the blade sharpener. In Fig. 14, the raised portions 52 are somewhat in the form of a double V and, as the blade moves over the sharpener, the edge of the blade moves along the high portions 52 from the ends 62 and 63 toward the center 64 and then toward the ends 65 and 66 of the inverted V. Whatever form the raised portions of the sharpener may take, that is, no matter whether a single or a double V is used, it is preferred that the raised portions 52 be spread apart and then converge and the ends of the V and the point 64 should be so placed on the sharpener with relation to the distance travelled by the sharpener during its reciprocation that all portions of the blade edge contact with the raised portions 52 at some time during the stroke of reciprocation, that is, the point or base 64 of the V should not be placed so far to the rear of the sharpening plate that when the sharpening plate is at its foremost point, for example, in the position shown in Fig. 5, the central part of the edge of the blade has not yet come into contact with a part of the raised portion of the sharpener. In the preferred form of the sharpener, the raised portion begins and ends substantially at the forward corners of the sharpener and from these forward corners converges symmetrically to the point 64 which is preferably midway between the sides of the sharpener. The edge of the blade, therefore, first contacts with two parts of the raised portions 52 and then contacts with the central portion 64 as it moves across and in contact with, the sharpener. Since the sharpener is movably mounted on the screw 17 or pivot pin 26, so that it can adjust itself to lie substantially parallel to the edge of the blade, the raised portions 52 of the sharpener will bear evenly against the edge of the blade, irrespective of how much the blade is warped and where the warp in the blade happens to be. The screw 17 or pivot pin 26 is preferably midway between the sides of the sharpener and midway between the sides of the blade when it is properly in the blade holder and at a right angle to both the front edge of the sharpener and the cutting edge of the blade. In this way the pivot on which the plate moves to adjust itself is symmetrically placed with regard to both the front and sides of both the sharpener and the blade. The point 64 is directly above the screw or pivot pin and the raised portions 52 are preferably placed symmetrically with regard to the screw 17 or pin 26, so that the pressure of the blade on the sharpener is brought to bear at equal distances from the pivot on which the sharpener moves to adjust itself for even contact with the blade, and the sharpener is balanced. With this construction the pressure between the blade edge and the raised portions is substantially equal at each point of contact, so that each half of the blade edge from the center outward is substantially equally sharpened and thus the sharpening of the blade is uniform or balanced. This even contact of the edge of the blade against the raised portions might not take place if there were more than two parts of the raised portions with which the edge of the blade could contact at any one time, because the edge of the blade might contact with two of the raised portions, but those two raised portions with which the contact was made might raise the edge of the blade above the other raised portion. During the reciprocation of the sharpener, therefore, the blade edge is supported at one time at two points and at another time at a single point but preferably at no time are there more than two points of contact or support between the edge of the blade and the sharpener. The surface of the raised portions is preferably rather broad and smoothly rounded or crowned and slopes gradually and smoothly down to the low portions 53 of the sharpener, so that there are no sharp corners which might injure or break up or bend the thin, delicate shaving edge of the blade. The high portions of the sharpener may be formed on the sharpener in any suitable manner. For instance, the low portions of the sharpener may be cut or ground out to leave the high portions, or the sharpener may be made in a stamping machine or die press in which the high and low portions are formed at the time that the sharpener is stamped out. A convenient method of making the sharpener and forming the high and low portions on the surface which contacts with the edge of the blade, and of assembling the sharpener 7 and the plate 8, is shown in Figs. 13 and 18. For this purpose, the sharpener 7 is stamped out with a sharpening surface having no high or low portions but with a projecting strip 67 on its under surface, which is substantially the form of the raised portion 52, which is desired on the surface of the sharpener. The sharpener 7 has studs 68 formed on its under surface, which enter suitably placed openings 69 in the plate 8 and which may be headed over to assemble the sharpener and plate. It has been found convenient to finish the sharpener by grinding the sharpening surface to a predetermined curve, substantially as shown at 70, and then bending the sharpener to produce the high and low portions. This is preferably accomplished by putting the assembled sharpener and plate 8 under a die, which will press down the low portions 53 and permit the high portions 52 to remain 150

substantially in their original position over the more or less obvious from an inspection of the drawings. The parts 4 of the handle are spaced near their upper ends by the stop pin 21 and by the shoulders which are formed near the ends of the rod 44 when the ends of the rod are reduced to give the squared ends 45. The parts 4 of the handle are spaced at their lower ends by the spacing block 73 and the shoulders which are formed on the pivot 11. In the form of razor shown in Figs. 1-5 which does not have the projecting ears 27 to align the guard teeth with the cutting edge of the blade by contact with the parts 5 of the handle, the base 74 of the stem 10 is preferably of such width that it just fits between the parts 4 of the handle so that the stem cannot twist and the guard is maintained parallel to the cutting edge of the blade. The block 73 is preferably made with knurling 75 to roughen it, so that it may be gripped very securely. The pivot 11 is preferably made with a flat face 76 and so placed in the razor that the flat face is toward the block 73 as is shown in the drawings, with the round surface uppermost. The lower end 74 of the stem 10 is bifurcated to provide the slot 77 which is enlarged and rounded at its inner end to fit over the pivot 11. In assembling the razor, the two parts 4 of the handle are fastened together by the rivets 78 with the spacing block 73 in between them and the parts 4 of the handle are so made that their tendency is to spring toward each other. The assembled sharpener 7, plate 8 and stem 10 are then held in a horizontal position, so that they extend to the rear of the razor and the slot 77 is slipped over the pivot 11 until the pivot 11 is seated in the rounded inner end of the slot. The upper parts 4 of the handle are then spaced apart, so that the assembled stem and sharpening plate can be brought substantially into the position shown in Fig. 5. The stop pin 21 is then seated in the opening in one of the parts 4 of the handle and the blade holder, with the rod 44 in it, is also placed in position with one of the squared ends 45 in one of the squared openings provided therefor. The upper parts of the handle 4 and the parts 6 are then permitted to spring together which seats the free ends of the pin 21 and the rod 44 in the holes in the handle. This assembles the razor. If desired, the ends of the stop pin 21 may be headed over on the outside of the parts 4 of the handle, in order to hold the parts of the handle together more securely, but ordinarily the spring of the parts of the handle is sufficient.

To provide a blade which is adjustable in width, for use with that form of razor which is shown in Figs. 19 and 20, on which the guard is not adjustable, the two wing-like parts of the connecting parts 30 may, if desired, touch lightly on the body portion of the blade with sufficient frictional contact to allow a person using the blade to force the body of the blade forward until the rear edges of the openings 71 engage the projections 72. The frictional engagement of the body portion of the blade with the wing-like parts of the connecting members 30, should not be enough to influence the flexibility of the body portion of the blade in any way, but should be only sufficient to hold the body of the blade and the backing in adjusted position with sufficient force to prevent the body from moving backward as the sharpener is reciprocated. The blade may thus be adjusted to give a close shave or a shave which is not so close, in the case where the guard is not adjustable. By forcing the body of the blade forward, the distance from the backing to the cutting edge of the blade may be increased and, therefore, when the blade is in the holder the cutting edge of the blade will project farther in front of the guard teeth than it otherwise would, to give a close shave. Likewise, the body of the blade may be forced backwardly so that the cutting edge is more guarded and the resulting shave will not be so close.

I claim:

1. A razor structure having mounted thereon a razor blade sharpener having high and low surface portions, the high portions having parts which contact with the shaving edge of the blade at the ends of the shaving edge and then converge while contacting with a shaving edge whereby the shaving edge is supported at one time at two places and another time at a single place as it moves with relation to the sharpener.
2. A razor structure having mounted thereon a razor blade sharpener having high and low surface portions, the high portions having parts which contact with the shaving edge of the blade at the ends of the shaving edge and then converge

- while contacting with a shaving edge whereby the shaving edge is supported by the high portions at one time at two places and at another time at a single place as it moves with relation to the sharpener there being at no time more than two parts of the high portions supporting the edge of the blade. 80
3. A razor structure having mounted thereon a razor blade sharpener having high and low surface portions, the high portions being continuous and having parts which contact with the shaving edge of the blade at the ends of the shaving edge and then converge while contacting with a shaving edge whereby the shaving edge is supported at one time at two places and at another time at a single place as it moves with relation to the sharpener. 85
4. A razor structure having mounted thereon a razor blade sharpener having high and low surface portions and adapted to sharpen a blade presenting an irregular shaving edge, the high portions having parts which contact with the shaving edge near the ends of the shaving edge and then converge while in contact with a shaving edge and the width of the high portions at any place where the shaving edge contacts therewith being less than the irregularities in the shaving edge. 90
5. A razor structure having mounted thereon a razor blade sharpener having high and low surface portions and adapted to sharpen a blade presenting an irregular shaving edge, the high portions having parts which contact with the shaving edge near the ends of the shaving edge and then converge while in contact with a shaving edge and the width of the high portions at any place where the shaving edge contacts therewith being less than the length of the shaving edge. 105
6. A razor structure having mounted thereon a razor blade sharpener having high and low surface portions, the high portion being in the form of converging ridges at an angle to the shaving edge of the blade as the blade moves relatively to the sharpener and the width of the high portion at any place where the shaving edge of the blade contacts therewith being less than the irregularities in the shaving edge. 115
7. A razor structure having mounted thereon a razor blade sharpener having high and low surface portions, the high portion being in the form of converging ridges and the width of the high portion at any place where the shaving edge of the blade contacts therewith being less than the irregularities in the shaving edge and the difference in height between the high and low portions being at least equal to the irregularities of the blade edge. 120
8. A razor structure having mounted thereon a sharpener for a razor blade having a sharpening surface presenting a curved elevated portion substantially in the form of a V for reciprocation relatively to and in contact with the edge of the blade. 125
9. A razor structure having mounted thereon a razor blade sharpener having corners and presenting high and low surface portions, the high portions forming an elevated ridge substantially joining the corners of the sharpener and extending toward the center of the sharpener between the corners. 130
10. A razor structure having mounted thereon a razor blade sharpener having corners and presenting high and low surface portions, the high portions forming a continuous elevated ridge sub- 135
- stantially joining the corners of the sharpener and extending toward the center of the sharpener between the corners for continuous contact with the edge of the blade as the blade and sharpener move relatively to each other. 140
11. A razor structure having mounted thereon a razor blade sharpener having corners and presenting high and low surface portions, the high portions forming an elevated ridge substantially joining a pair of the corners of the sharpener and extending toward the center of the sharpener between the corners. 145
12. A razor structure having mounted thereon a razor blade sharpener having corners and presenting high and low surface portions, the high portions forming an elevated ridge substantially joining the pair of corners of the sharpener which are in line with the edge of the blade and extending toward the center of the sharpener between the corners. 150
13. A razor including a blade holder, and a blade sharpener mounted thereon for reciprocation relatively to the blade and in contact therewith by shaking the razor, and the sharpener and blade also being relatively movable to permit the sharpener and blade to lie in parallel contact with each other, a sharpener having high and low surface portions, the high portions having parts which contact with the shaving edge of the blade at the ends of the shaving edge and then converge whereby the shaving edge is supported at one time at two places and at another time at a single place as it moves with relation to the sharpener, there being at no time more than two parts of the high portions supporting the edge of the blade. 155
14. A razor including a blade holder, and a blade sharpener mounted thereon for reciprocation relatively to the blade and in contact therewith by shaking the razor, and the sharpener and blade also being relatively movable to permit the sharpener and blade to lie in parallel contact with each other, a sharpener having high and low portions adapted to sharpen a blade presenting an irregular shaving edge, the high portions having parts which contact with the shaving edge at the ends of the shaving edge and then converge and the width of the high portions at any point where the shaving edge contacts therewith being less than the irregularities in the shaving edge. 160
15. A razor including a blade holder and a razor blade sharpener adapted to reciprocate relatively to and in contact with the blade, a sharpener having high and low surface portions, the high portions having parts which contact with the shaving edge of the blade at the ends of the shaving edge and then converge whereby the shaving edge is supported at one time at two places and at another time at a single place as it moves with relation to the sharpener. 165
16. A razor including a blade holder and a razor blade sharpener adapted to reciprocate relatively to and in contact with the blade, the sharpener having high and low surface portions and being adapted to sharpen a blade presenting an irregular shaving edge, the high portions having parts which contact with the shaving edge at the ends of the shaving edge and then converge and the width of the high portions at any point where the shaving edge contacts therewith being less than the irregularities in the shaving edge. 170
17. A razor including a blade holder and a razor blade sharpener adapted to reciprocate relatively to and in contact with the blade, the 175

- sharpener having high and low surface portions, the high portions having parts which contact with the shaving edge of the blade at the ends of the shaving edge and then converge whereby the shaving edge is supported at one time at two places and at another time at a single place as it moves with relation to the sharpener, the relative movements of the sharpener and blade being so limited that the blade is in continuous contact with the high portions of the sharpener.
18. A razor including a holder and a razor blade sharpener adapted to reciprocate relatively to and in contact with the blade, the sharpener having high and low surface portions, the high portions having parts which contact with the shaving edge of the blade at the ends of the shaving edge and then converge whereby the shaving edge is supported at one time at two places and at another time at a single place as it moves with relation to the sharpener, the relative movements of the sharpener and blade being so limited that the blade edge is in continuous contact with the high portions whenever the blade edge contacts with the sharpener.
19. A razor including a blade holder and a razor blade sharpener adapted to reciprocate relatively to and in contact with the blade, the sharpener having high and low surface portions, the high portion forming a ridge at an angle to the shaving edge of the blade as the blade moves relatively to the sharpener, and the width of the high portion at any place where the shaving edge of the blade contacts therewith being less than the irregularities in the shaving edge.
20. In a self sharpening safety razor having a blade presenting a cutting edge and a sharpener reciprocable relative to and in contact with the cutting edge and having a guard adjacent to the cutting edge, supporting means for supporting the sharpener, and connecting means connecting the sharpener and supporting means and movable to adjust the position of the guard relative to the cutting edge.
21. In a razor having a blade and a sharpener mounted on the razor for relative reciprocation and having the blade and sharpener relatively movable to permit the sharpener and blade edge to lie substantially parallel to each other, raised portions on the sharpener for contact with the blade edge during the relative reciprocation of the blade and sharpener, the raised portions on the sharpener converging and being arranged substantially symmetrically with respect to the sides of the sharpener.
22. In a razor having a blade and a sharpener mounted on the razor for relative reciprocation and having the blade and sharpener relatively movable to permit the sharpener and blade edge to lie substantially parallel to each other, raised portions on the sharpener for contact with the blade edge during the relative reciprocation of the blade and the sharpener, the raised portions on the sharpener converging and being arranged substantially symmetrically with respect to the sides of the blade.
23. In a razor having a blade and a sharpener mounted on the razor for relative reciprocation and having the blade and sharpener relatively movable to permit the sharpener and the blade edge to lie substantially parallel to each other, raised portions on the sharpener for contact with the blade edge during the relative reciprocation of the blade and sharpener, the raised portions on the sharpener converging and being arranged sub-
- stantially symmetrically with respect to the cutting edge of the blade.
24. In a razor having a blade and a sharpener mounted on the razor for relative reciprocation and having the sharpener pivoted to permit the sharpener to adjust itself to lie substantially parallel to the cutting edge of the blade, raised portions on the sharpener for contact with the blade edge during the relative reciprocation of the blade and sharpener, the raised portions on the sharpener converging and being arranged symmetrically with respect to the pivot.
25. In a razor having a blade and a sharpener mounted on the razor for relative reciprocation and having the sharpener pivoted along a line at a right angle to the front of the sharpener to permit the sharpener to adjust itself to lie substantially parallel to the cutting edge of the blade, raised portions on the sharpener for contact with the blade edge during the relative reciprocation of the blade and sharpener, the raised portions being arranged symmetrically with respect to the pivot line and converging to a point lying above the pivot line.
26. In a razor having a blade and a sharpener mounted on the razor for relative reciprocation and having the sharpener pivoted along a line at a right angle to the cutting edge of the blade to permit the sharpener to adjust itself to lie substantially parallel with the cutting edge of the blade, raised portions on the sharpener for contact with the blade edge during the relative reciprocation of the blade and sharpener, the raised portions converging symmetrically to a point lying above the pivot line.
27. In a razor having a blade and a sharpener mounted on the razor for relative reciprocation and having the sharpener pivoted on a pivot symmetrically placed with respect to the cutting edge of the blade to permit the sharpener to adjust itself to lie substantially parallel to the cutting edge, raised portions on the sharpener for contact with the blade edge during the relative reciprocation of the blade and sharpener, the raised portions converging and being symmetrically placed with respect to the pivot.
28. In a self sharpening safety razor having a blade presenting a cutting edge and a sharpener reciprocable relative to and in contact with the cutting edge and having a guard adjacent to the cutting edge, supporting means for supporting the sharpener, and connecting means connecting the sharpener and supporting means and on which the sharpener is movable to permit the sharpener to lie substantially parallel to the cutting edge of the blade, the connecting means being movable to adjust the position of the guard relative to the cutting edge.
29. A razor blade having a body portion, a backing spaced from the body portion, connecting parts extending over the body portion from the backing at spaced points, and cooperating openings and projections on the body portion and connecting parts to lock the body portion to the backing.
30. A razor blade having a body portion, a backing spaced from the body portion, connecting parts extending from the backing at spaced points over the body portion without gripping the body portion, and cooperating openings and projections on the body portion and connecting parts to lock the body portion to the backing.
31. A razor blade having a body portion, a backing spaced from the body portion, connecting parts extending from the backing at spaced points over the body portion without gripping the body por-

- tion, and cooperating openings and projections on the body portion and connecting parts to lock the body portion to the backing, the projections being smaller than the openings to permit a slight amount of play.
32. A razor blade having a body portion, a backing spaced from the body portion, connecting parts extending from the backing at spaced points over the body portion without gripping the body portion, and cooperating interlocking means on the body portion and connecting parts to lock the body portion to the backing.
- 10 33. A razor blade having a body portion, a backing spaced from the body portion, connecting parts extending from the backing at spaced points over the body portion without gripping the body portion, and cooperating loosely interlocking means on the body portion and connecting parts to lock the body portion to the backing.
- 20 34. A razor blade presenting a cutting edge and a rear portion adapted to seat in a blade holder, the rear portion presenting two projecting seating points for contact with the blade holder.
- 25 35. A razor blade presenting a cutting edge and a rear portion adapted to seat in a blade holder, the rear portion being cut away at the center to prevent seating contact with the blade holder except near the ends of the rear portion, to prevent rocking of the blade in the blade holder.
- 30 36. A razor blade having a body portion and a backing adapted to be gripped at its central portion by a blade holder and presenting two seating points substantially at its ends to provide a positive positioning of the blade with respect to the blade holder.
- 35 37. A razor blade presenting a cutting edge and a rear portion, the rear portion having an indented central part adapted to be gripped by a blade holder and having two seating portions for seating contact with the blade holder spaced at either side of the central part.
- 40 38. A razor blade having a body portion presenting a cutting edge and a rear portion thicker than the body portion, the rear portion being tapered from its central part toward its ends and a ridge on the rear portion adapted to cooperate with a part on a blade holder to hold the blade in the blade holder.
- 45 39. A razor blade having a cutting edge and an enlarged rear portion adapted to be gripped by a blade holder, the enlarged portion being cut away to present two spaced points for contact with the holder to align the edge of the blade with the blade holder.
- 50 40. A razor blade having a cutting edge and an enlarged rear portion adapted to be gripped by a blade holder, the enlarged portion being pointed at both ends to facilitate insertion in the blade holder.
- 80 41. A razor blade having a cutting edge and an enlarged rear portion adapted to be gripped by a blade holder, the enlarged portion being widest near its central part in order to be most firmly gripped by the blade holder at that point.
- 85 42. A razor blade having a cutting edge and a rear portion presenting two projecting seating points for contact with the blade holder, and cooperating means on the blade holder and said rear portion for forcing said seating points against the blade holder.
- 90 43. A razor including a blade holder and a razor blade sharpener adapted to reciprocate relatively to and in contact with the blade, the sharpener having high and low surface portions, the high portions being adapted to continuously contact with the blade edge at two small areas and then at a single larger area at least as large as the total area of the said two small areas.
- 95 44. A razor structure having mounted thereon a blade sharpening element and a blade holding element, said blade sharpening element presenting high and low surface portions, the high portions having parts arranged to contact with the shaving edge of a blade at not more than two places at one time as it moves with relation to the blade, said elements being mounted on the structure to permit even contact between the blade edge and high surface portions by relative tilting.
- 100 45. A razor structure including a blade element and a blade sharpening element, said blade sharpening element presenting high and low surface portions, the high portions having parts which contact with the shaving edge of the blade near the ends of the shaving edge and then at the center as it moves with relation to the sharpener whereby the shaving edge is supported at not more than two places during such movement, said elements being mounted on the structure and relatively tiltable.
